UNITED STATES PATENT OFFICE.

RAYMOND L. GRUSS, OF SAN FRANCISCO, CALIFORNIA, ASSIGNOR, BY MESNE ASSIGNMENTS, TO GRUSS AIR SPRING COMPANY OF AMERICA, OF SAN FRANCISCO, CALIFORNIA, A CORPORATION OF CALIFORNIA.

AIR SPRING.

Application filed September 10, 1924. Serial No. 736,883.

This invention relates to cushioning devices, shock absorbers and the like, and more particularly to the types which employ air as a cushioning medium and are known as 5 air springs.

The object of the present invention is to generally improve and simplify the construction and operation of air springs of the character described; to provide a spring which 10 will efficiently cushion ordinary road shocks and which will also check rebound movements; to provide a piston structure which will reduce wear on the cup-leathers or other packing employed to a minimum; to provide 15 a piston and packing structure which will reduce leakage of the sealing oil to a large extent, and further, to provide means for automatically returning the major portion of such sealing oil as may leak or escape by the piston 20 structure.

One form which my invention may assume is exemplified in the following description and illustrated in the accompanying drawings, in which—

25 Fig. 1 is a central vertical longitudinal section of the air spring.

Fig. 2 is a similar section showing a modified form of piston structure.

Referring to the drawings in detail, and 30 particularly to Fig. 1, A indicates in general a bottle or cylinder which is secured in a lower cylindrical casing B. The bottle A may be constructed of seamless steel tubing or the like, while the casing B may be constructed of cast-iron, the bottle and the casing being joined or secured with relation to each other by means of a threaded connection as at 2. The inner surface of the casing B is provided with a pad 3 and it is secured to the 35 forward end of a vehicle frame, such as indicated by dotted lines at 4, by means of an intermediate plate 5 secured to the pad by means of bolts 6.

The cylinder is divided into three compartments, generally indicated at 7, 8 and 9. The compartments 8 and 9 are of uniform 45 diameter, while the compartment 7 is slightly smaller. The upper end of the cylinder is closed by means of a rounded head member 10 and an inflating valve 11 is placed in the upper end thereof to permit air under pressure 50 to be introduced.

Division of the cylinder or bottle A into

three chambers is accomplished by the use of two pistons generally indicated at 12 and 13. These pistons are carried by a rod 14, which is connected to the springs of a vehicle indicated by dotted lines at 15 in any suitable manner; for instance, by forking the lower end of the rod as shown at 16. The lower end of the cylindrical casing B is closed by means of a head member 17. A bearing 18 is formed centrally of the head member and a bearing bushing 19 extends therethrough. The rod 14 passes through the head and the bushing, and is guided and supported thereby. The piston 12 consists of an upwardly turned cup leather and it is secured to the rod 14 by means of a plate and a nut 20. The upper end of the rod 14 is shouldered, as 70 shown, to form a support for a cup-shaped member 21. This member extends downwardly exteriorly over the bushing 19 and it terminates in a pair of annular shoulders such as indicated at 22 and 23, these shoulders forming a seat for a downwardly turned cup leather 24 and an upwardly turned cup leather 25, the cup leathers 24 and 25 constituting the piston 13. The upper cup leather 25 is separated from the cup leather 75 24 by means of a central disk 26 and it is secured on the disk 26 by means of a spacing sleeve 27. The upper end of this sleeve is enlarged or expanded, as shown at 28, and as such forms an annular bearing contact 80 with the interior surface of the cylinder 7, thereby relieving the cup leather of the upper piston from any side thrust or wear.

The cup-shaped member 21, which terminates in the lower annular shoulders 22 and 23, also serves as a bearing member to relieve the lower cup leathers 24 and 25 of side thrust and wear; that is, the lower portion 23 engages the inner surface of the cylinder chambers 8 and 9 and as such takes off all wear 85 at this point. The pistons are furthermore guided by means of the bushing 19, as this not only guides the rod 14 but also the cup-shaped sleeve 21 and the spacing sleeve 27.

In actual practice, with the parts assembled 100 as shown in Fig. 1 and mounted on an automobile, it will be understood that the upper cylinder 7 is partially filled with a heavy lubricating oil or grease such as indicated at 30. This grease or oil forms a seal above the 105 pistons 12 and thereby permits the introduc-

tion of air under pressure through the valve 11, the air thus admitted having a sufficient pressure to cushion or sustain the load imposed on the spring 15. The sealing oil sometimes gets fairly thin, through heat and friction, and has a slight tendency to leak by the cup-leather 12. Any such leakage or escape of the oil will permit the oil to drain into the intermediate cylinder chamber 8. It is here 10 caught by the upturned cup-leather 25 and cannot readily escape. Any oil escaping by the upper piston will gradually accumulate in the chamber 8 and it will be automatically returned to the upper cylinder chamber 7 15 when a sufficient amount of oil is collected; that is, the cylinder chamber 8 presents two chambers of varying areas. The lowermost position assumed by the pistons 12 and 13 determines the largest capacity of the cylinder chamber 8, but any outward movement of the pistons reduces this capacity, due to the differential action between the chambers of varying diameters. In other words leakage oil accumulating in the chamber 8 will be 20 forced back into the upper chamber 7 during upward movement of the pistons, as the reduced area will produce such a pressure as to force the oil upwardly by the upturned cup-leather of the upper piston and it is thus 25 automatically returned from time to time to the upper cylinder chamber 7 where it will continue to perform its function. An exceedingly small amount of oil will, of course, in time escape past the cup-leathers 24 and 25. 30 Such oil will accumulate in the lower chamber 9 and it may take months before a sufficient amount has collected to warrant its removal. This is accomplished by merely opening the plug 31 so that the oil may be drained off; that is, any excess accumulation of oil in the lower chamber 9 would be detrimental as it would hydraulically lock the pistons against movement, and it should for this reason be removed from time to time. The oil 40 cannot escape from the lower chamber 9, as it would have to rise up over the upper edge of the bushing 19 and then escape downwardly between the bushing and the rod 14. Such escape of the oil is very unlikely and it might 45 therefore be stated that the spring is, practically speaking, leak-proof as far as oil is concerned and as such will not be mussed up with dust accumulating on surfaces covered with oil by leakage and so on.

50 The lower chamber 9 does not only serve the function of a trap for the accumulation of any oil which may finally escape by the upper and lower pistons, but it also serves the function of a compression chamber to 55 check rebound movements. Rebound movement will cause upward movement of the cylinders and downward movement of the pistons. Air contained in the cylinder chamber 9 will thus be placed under compression

and rebound movements will accordingly be checked. Ordinary road shocks are cushioned by the air in the upper cylinder 7, as this compresses and expands in proportion to the road shocks encountered.

The structure shown is exceedingly simple; it is compact and rigid in construction; ample bearing surfaces are provided to take care of all side thrust and strains; the packing medium, to-wit, the cup-leathers employed are relieved of all side thrust by the bearing bushing 19 and the piston extensions 23 and 28 and as such are only subject to natural wear caused by reciprocal motion. The life of the springs should accordingly be materially increased and leakage of sealing oil should be reduced to a minimum. All parts should be amply lubricated as oil cannot escape, except by drainage through the plug 31, and as all parts are closed to the atmosphere it is obvious that dust and grit cannot enter and do damage.

The structure shown in Fig. 2 functions in a manner identical to that described in Fig. 1. The only difference between the two structures is caused by the elimination of the cup-shaped sleeve 21 and the spacing sleeve 27. These are done away with by forming shoulders on the rod indicated at 14^a, the shoulders being shown at 40 and 41. A collar 42, seated on the upper shoulder 41, serves as a bearing and guide for the upper end of the rod 14^a and it also serves as a seat and support for the upper cup-leather. The lower collar 40 forms a seat for a bearing member 43^a and this in turn forms a seat for the cup-leathers indicated at 44 and 45, these cup leathers, together with the bearing ring 43, being secured in position by means of a nut 46. The bushing 19 is not entirely eliminated in this instance, but it is materially reduced in length as shown at 19^a.

While certain features of the present invention are more or less specifically illustrated, I wish it understood that various changes in form and proportion may be resorted to within the scope of the appended claims. I similarly wish it understood that the materials and finish of the several parts employed may be such as the experience and judgment of the manufacturer may dictate or various uses may demand.

Having thus described my invention, what I claim and desire to secure by Letters Patent is—

1. An air spring of the character described comprising an elongated cylinder divided into upper and lower sections of varying diameter and the upper section presenting the smallest diameter, a head forming a closure for the upper cylinder section, a piston rod extending through the lower cylinder section and into the upper section, said rod being of smaller diameter than the upper cylinder section, a piston on the upper end of the rod

- and operating within the upper section of the cylinder only, a second piston on the rod and operating in the lower cylinder section only, an upwardly turned cup-leather carried by 5 the upper piston, a pair of cup-leathers carried by the lower piston, said cup-leathers being reversed so that one extends upwardly and one downwardly, a metallic annular extension on the upper piston forming a bearing 10 for the upper cup-leather to relieve the same of all side thrust, and a metallic annular bearing extension on the lower piston to relieve the lower pair of cup-leathers of side thrust.
- 15 2. An air spring of the character described comprising an elongated cylinder divided into upper and lower sections of varying diameter and the upper section presenting the smallest diameter, a head forming a closure 20 for the upper cylinder section, a piston rod extending through the lower cylinder section and into the upper section, said rod being of smaller diameter than the upper cylinder section, a piston on the upper end of the rod 25 and operating within the upper section of the cylinder only, a second piston on the rod and operating in the lower cylinder section only, an upwardly turned cup-leather carried by the upper piston, a pair of cup-leathers 30 carried by the lower piston, said cup-leathers being reversed so that one extends upwardly and one downwardly, a metallic annular extension on the upper piston forming a bearing for the upper cup-leather to relieve 35 the same of all side thrust, a metallic annular bearing extension on the lower piston to relieve the lower pair of cup-leathers of side thrust and a bushing carried by the cylinder, said bushing forming a bearing and 40 guide for the piston rod.
3. An air spring of the character described comprising an elongated cylinder divided into upper and lower sections of varying diameter and the upper section presenting the 45 smallest diameter, a head forming a closure for the upper cylinder section, a piston rod extending through the lower cylinder section and into the upper section, said rod being of smaller diameter than the upper cylinder 50 section, a piston on the upper end of the rod and operating within the upper sec-
- tion of the cylinder only, a second piston on the rod and operating in the lower cylinder section only, a head member on the lower end of the cylinder, and an elongated bearing bushing therein through which the piston rod extends, said lower head member forming a compression chamber in the lower end of the cylinder to check recoil movement. 55
4. An air spring of the character described comprising an elongated cylinder divided into upper and lower sections of varying diameter and the upper section presenting the smallest diameter, a head forming a closure 60 for the upper cylinder section, a piston rod extending through the lower cylinder section and into the upper section, a piston on the upper end of the rod and operating within the upper section of the cylinder only, a second piston on the rod and operating in the lower cylinder section only, and a bushing 65 secured within the cylinder and extending upwardly therein to the upper section of the cylinder, said bushing forming a bearing and guide for the piston rod and relieving 70 the upper and lower pistons of side thrust.
5. An air spring of the character described comprising an elongated cylinder divided into upper and lower sections of varying diameter and the upper section presenting the 75 smallest diameter, a head forming a closure for the upper cylinder section, a piston rod extending through the lower cylinder section and into the upper section, said rod being of smaller diameter than the upper cylinder section, a piston on the upper end of the rod and operating within the upper section of the cylinder only, a second piston on the rod and operating in the lower cylinder section only, cup-leather packing members on 80 each piston, metallic bearing sections on each piston and engaging the respective cylinder bores, said bearing sections relieving the cup-leather packings of side thrust, and an elongated bushing secured to the lower cylinder head, said bushing forming a guide 85 and bearing for the piston rod and absorbing all side thrusts transmitted thereto, said bushing member also relieving the pistons of side thrust. 90
